N° 963
William P. Coggshall's Design for a Stove.

Patented Nov. 3. 1857.

Fig. 2.

Fig. 1.

Des. 963

Wm. S. Coggeshall, of Fall River, Mass.
Letters-Patent No. 963. Dated Nov. 3rd 1857.

The schedule referred to in these Letters-Patent and making part of the same.

To all persons to whom these presents shall come:-

Be it known that I, William S. Coggeshall, of Fall River, in the county of Bristol, and state of Massachusetts, have invented or produced a new and original design for a stove, such being exhibited in the accompanying drawings, of which,

Figure 1. denotes a front elevation of the stove, as seen in perspective.

Figure 2. a transverse section of the front half of the stove.

Although in Figure 1. the words Patent Applied For, Fall River Foundry Co. appear, in relief, they are not to be included in the Design.

The door which is represented as open or turned back has the same design or configuration on its front as is given to the upper door. While the general and particular ornamentation of the different parts of the body of the stove is shown by Figure 1. with sufficient exactness to enable a stove pattern maker to produce the design the section exhibited in figure 2. shows the general and particular projections of the mouldings of the base, body, cap-plate and fun of the stove, as also the design for the legs.

I claim the design of the base-plate, each of the doors, door frame, the cap-plate, constituting a design for stoves, as shown in the drawings.

End

I, M. P. hereunto set my signature, this 7th day of July A. D. 1857.

Witnesses

Thos. J. Pickering
Simeon Borden

In testimony whereof, I have

Wm. S. Coggeshall
